UNITED STATES PATENT OFFICE.

RAY HAGADONE, OF COEUR D'ALENE, IDAHO.

SAW-TOOTH GAGE.

1,317,873.

Specification of Letters Patent.

Patented Oct. 7, 1919.

Application filed August 16, 1916, Serial No. 115,303. Renewed February 24, 1919. Serial No. 278,936.

To all whom it may concern:

Be it known that I, RAY HAGADONE, a citizen of the United States, residing at Coeur d'Alene, in the county of Kootenai 5 and State of Idaho, have invented new and useful Improvements in Saw-Tooth Gages, of which the following is a specification.

This invention relates to improvements in saw gages, primarily adapted for use in the 10 straightening or shaping of the teeth of band saws and gang saws.

An object of the invention contemplates the provision of a gage embodying a movable gage member through which the saw 15 teeth pass, and adapted for vertical adjustment to suit the character of the teeth, in order that the different types of the teeth may be accurately and readily determined without the necessity of the operator using 20 his eyes for such purpose.

A further object of the invention resides in providing the gage member of a tapering formation and with a slot, and adapted to be either raised or lowered for accommodating 25 saws of different thickness, further the different degrees of swaging or spreading at the cutting point of tooth.

Another object of the invention resides in providing a frame having a series of 30 indent contact points adapted for engagement with one of the side faces of the saw during the gaging act of the teeth, thus retaining the proper position of the saw at all times.

With the above and other objects in view, 35 the invention consists in the novel features, details of construction and combination of parts which will hereinafter be more fully set forth, illustrated in the accompanying drawing and pointed out in the appended 40 claim.

Figure 1 is a rear elevation of the gage; Fig. 2 is a front elevation;

Fig. 3 is a top plan view with the gage member removed; and

45 Fig. 4 is a perspective view of the gage member.

Referring more particularly to the accompanying drawing, in which like characters of reference refer to corresponding parts in 50 the several views, 5 denotes my improved band saw tooth gage generally, comprising a flat plate constructed preferably of metal or the like material. Depending from the 55 lower edge of the plate is a substantially rectangular foot 7, to which is secured on the

outer face thereof, by means of fasteners 8, a hand grip 9. The body portion 10 of the frame is extended in opposite lateral directions to provide at the upper end of the 60 frame a pair of horizontally aligned arms 11 and 12 respectively. The horizontal portion 13 of each of said arms serves as a cap, whereby upon the sliding of the gage along the sides of the saw, the caps or horizontal 65 portion 13 of the arms will overlie the teeth of the saw and serve to an extent as a guide for the gage upon the active use of the same. The upper edge of the body portion, at a point between the spaced arms 11 and 12, is 70 cut out as at 14, and serves to an extent as a sight opening, that is to say, when the gage is in applied position, the cut out portion 14 will permit of the user observing the teeth of the saw, thus preventing any undue 75 mutilation of the teeth, should the swaging or setting of the teeth be improperly performed. At a point in adjacent relation to the sight opening 14, I provide an elongated vertically disposed slot 15 opening out 80 through the upper edge of the body portion 10 at a point between the arms 11 and 12. The purpose of this slot will be more fully set forth as the description of the invention is proceeded with. Connected exteriorly of the body portion in juxtaposition to the sight opening 14 and flush with one of the side walls forming the slot 15, by means of a slot 18, is a movable gage member 17. The screw 16 which connects the 85 movable gage member with the frame, protrudes through the elongated slot 18 formed in the front plate 19 of the movable gage member 17. One of the longitudinal edges of the plate 19 is provided with an extension 90 20. This extension is bent at right angles with respect to the plate 19, permitting the extension to slidably operate in the slot 15 upon the adjustment of the screw 16. The extension 20 is provided with a slot 21 opening out through the bottom edge 22 of the extension and through which the teeth of the saw pass during the gaging operation thereof. It will be clearly understood by those skilled in the art to which the invention relates that should the correct shaping or wedging of the teeth be improperly performed, the user of the device can readily and easily ascertain such fact due to the formation of the closed end of the slot 21. 105 At this point, it may be stated that the specific construction of slot 21 permits of

obtaining a coarser or finer gage of the saw teeth upon the vertical adjustment of the gage member 17 with respect to the arms 13. The frame 6 is provided with a series of 5 inturned projections 23, adapted in the use of the gage, to contact with the sides of the saw, while the surface of the teeth passes through the gage slot 21, thereby 10 gaging the saw in a positive and uniform position during the entire process of gaging.

The type of saw gage illustrated in the accompanying drawing is primarily adapted for use on band and gang saws for the purpose of locating the teeth that are out of 15 alignment.

From the foregoing description, taken in connection with the accompanying drawing, the advantages of construction and of the 20 method of operation will be readily apparent to those skilled in the art to which the invention relates, and while I have described the principles of operation of the

invention, together with the device which I now consider to be the best embodiment 25 thereof, I desire to have it understood that the device shown is merely illustrative, and that such changes may be made when desired as are within the scope of the 30 appended claim.

I claim:

In a gage, the combination with a frame having along its upper edge a pair of spaced arms and a slot opening out through the upper edge thereof at a point between said 35 arms, of a gage member therefor, means connecting the gage member to the frame for vertical adjustment, said gage member being provided with an extension arranged at right angles with respect to the frame 40 and provided with a slot diverging in a direction toward the lower end of the extension, a portion of the extension fitting in the slot of the frame.

In testimony whereof I affix my signature. 45
RAY HAGADONE.
